CARBURETOR

Andre J. E. Roualet, Detroit, Mich., assignor to
 Chrysler Corporation, Detroit, Mich., a corpora-
 tion of Delaware

Application February 27, 1931. Serial No. 518,609

6 Claims. (Cl. 261—50)

This invention relates to an improved carburetor and particularly to improved means in a carburetor for selectively conditioning it for starting and normal running operations.

- 5 In starting an internal combustion engine, it has been common practice to meter the fuel for the starting and normal running mixtures by a single metering orifice in the fuel system and to control the rate of flow of fuel to the mixing 60 chamber by regulating the suction therein with a choke valve. The suction in a carburetor builds up rapidly during the follow-through stage of starting which occurs after the initial explosions and as a result, a metering orifice, which is suitable for regulating the flow of fuel during normal 65 running of an engine, permits an excessive flow of fuel during the follow-through stage when, as a matter of fact, a mixture having a fuel ratio lower than that required for the initial explosion 70 is advantageous. Excessive fuel richness during the follow-through stage causes the cylinders and intake manifold of the engine to load up, particularly during low temperature starting and frequently starting is unsuccessful for this reason.
- 25 When the starting fuel supply is discharged through a main fuel nozzle of the air bleed type, atomization of the fuel and other advantages of air bleeding it are not obtainable, for the flow of air to the outlet of the air bleed is cut off by 75 the choke valve. This reduction in air flow in the mixing chamber decreases atomization of the starting fuel supply whether it is discharged from an air bleed or from a nozzle of the non-air bleeding type.

- 35 The main objects of the invention are to provide means in a carburetor for selectively conditioning it for starting and for normal running operation; to provide means of this kind which will not disturb a predetermined normal running 80 fuel mixture; to provide an auxiliary starting fuel system in a carburetor which is metered independently of the normal or main fuel system; to provide an auxiliary fuel system which has an independent air bleed so as to supply air to the 85 starting fuel discharge for atomizing it when the choke valve is closed; to provide means for closing the normal fuel system when the carburetor is conditioned for starting by closing of its choke 90 valve; and to provide means for alternatively 95 rendering the normal and starting fuel systems inoperative as the carburetor is conditioned, by the choke valve, for starting and normal operation, respectively.

- Other objects of the invention are to provide 95 an auxiliary air inlet to the mixing chamber for

predetermining the air factor of the starting fuel mixture while the fuel is metered when the choke of the carburetor is closed during starting; to provide an auxiliary air inlet of this kind which is controlled by the suction in the mixing chamber of the carburetor so as to proportion the air supply during starting with the fuel supplied by the carburetor suction; and to provide air controlling means of this kind which is adapted to regulate the air supply to the mixing chamber of a carburetor when the choke is only partly open during the warming up stage which follows starting of the engine.

An illustrative embodiment of the invention is shown in the accompanying drawings, in which:

Fig. 1 is a side elevation of an internal combustion engine which is equipped with my improved carburetor.

Fig. 2 is a vertical section showing a carburetor which embodies my invention in condition for normal operation.

Fig. 3 is a vertical section of the fuel nozzle of the carburetor shown in Fig. 2.

Fig. 4 is an enlarged fragmentary view of the choke valve of the carburetor showing an auxiliary air inlet valve in detail.

Fig. 5 is a view similar to Fig. 2, but showing the carburetor conditioned for starting.

Fig. 6 is a fragmentary vertical section showing a carburetor which embodies another form of the invention in condition for normal operation.

Fig. 7 is a view similar to Fig. 6, but showing the carburetor in condition for starting.

In both forms shown in the drawings, a down draft carburetor is illustrated, but substantially the same starting mixture producing apparatus may be applied to a conventional up draft carburetor without changing the main features of the invention. The carburetor illustrated in Figs. 2 to 5 inclusive, includes a central body portion 1 with which is integrally formed a tubular structure 2 having a direct passage which is provided at its upper end with an air inlet 3 and at its lower end with a fuel mixture outlet 4. The outlet end of the tubular structure 2 has a radial flange 5 by which it is mounted on a neck 6 of an intake manifold 7, as shown in Fig. 1, with the outlet 4 communicating with the intake manifold. Mounted on the inlet end of the tubular structure 2 is an air cleaner 8.

A shaft 9 which carries a butterfly type choke valve 10 extends transversely of the tubular structure 2 and is located in close proximity to its upper end. This valve is provided with an

- aperture 11 across which radial ribs 12 extend. The ribs 12 are integrally joined at the center of the aperture 11 by a small disc 13 having an opening 14 through which a valve stem 15 passes.
- 5 Formed on the lower end of the valve stem 15 is a valve plate 16 which is normally held in a closed position and against the lower side of the choke valve by a spring 17 that bears between a collar 18 on the upper extremity of the valve stem and a washer 19 that is seated upon the upper side of the disc 13. The spring 17 yieldably holds the valve 16 in a closed position. Located at the outlet end 4 of the tubular structure 2 is a butterfly type of throttle valve 20 which is carried 10 by a shaft 21 that extends transversely of the tubular structure 2 and which is rotatably mounted in the walls thereof. The interior of the tubular structure 2 provides a mixing chamber 22 in which fuel and air are mixed together 15 before they are fed to the intake manifold of the engine.
- The carburetor includes a fuel reservoir 23 which is formed integral with the central body portion 1 and spaced from the tubular structure 2. Formed in the lower end of the central body portion 1 is a well 24 which communicates through a passage 25 with the bottom of the reservoir. A fuel passage 26 which communicates at one end with the well 24 and at its other end with the interior of the mixing chamber 22 is also provided in the body portion of the carburetor. Located in the mixing chamber 22 is a Venturi throat 27 having an arm 28 on which is mounted a fuel nozzle 29. The arm and fuel nozzle 28 and 29 are provided with communicating passages 30 and 31 which also communicate with the fuel passage 26. The nozzle 29 has an air passage or bleed 32 which extends and opens into the mixing chamber at its upper end and which is closed at its lower extremity. 35 Transversely extending apertures 33 are formed in the partition 34 between the fuel passage 31 and air bleed 32 for admitting air into the fuel passage 31. This construction is typical of conventional air bleed nozzles which in some cases 40 communicate directly with the fuel passage of the body portion of the carburetor and extend into the mixing chamber at an inclination to the axis thereof, the particular construction shown being illustrative of a workable form.
- 45 The nozzle 29 and the passages by which it is connected with the well 24 form a normal fuel system for supplying fuel to the mixing chamber during normal operation of the engine. The lower end of the well 24 is closed by a threaded 50 plug 35 having a central bore 36 and a communicating peripheral groove 37. The peripheral groove 37 of the plug 35 communicates with a horizontal fuel passage 38 which leads to a vertical fuel passage 39 extending upwardly through the central body portion 1 of the carburetor. Threaded in the lower end of the body portion 1 of the carburetor is a metering screw 40 having a metering orifice 41 located at the junction 55 of the passages 38 and 39. The upper end of the vertical passage 39 communicates with an annular chamber 42 through which a pipe 43 passes. The tubular stem 43 extends through the body portion 1 of the carburetor and has an outlet 44 communicating with the mixing chamber 22. Formed on the other end of the stem is a threaded plug 45 having a restricted air inlet or bleed 46 that communicates with the atmosphere. That portion of the stem 43 which 60 is located in the annular chamber 42 is provided

with apertures 47 for admitting fuel from the passage 39 to the interior of the stem. The bore 36 and groove 37 of the plug 35, together with the passages 38 and 39 and the body portion of the carburetor and the passage through the stem 43 form an auxiliary starting fuel system which is adapted to introduce fuel into the mixing chamber independently of the main or normal fuel system.

8 Located in the well 24 at the junction of the normal and starting fuel systems, is a fuel valve 48 which is carried by a valve stem 49 that extends upwardly through a passage 50 in the body portion of the carburetor. This valve has a lower conical extremity 51 which registers with the bore 36 of the plug 35 and an upper conical extremity 52 which is adapted to seat upon a valve seat 53 at the upper end of the well 24. The valve 48 is normally held in its lower most position shown in Fig. 2, so as to close the starting fuel system, by a spring 54 which is located in the passage 50 and which surrounds the valve stem 49. The spring 54 bears between a collar 55 on the stem 49 and a plug 56 which is threaded in the upper end of the passage 50. When 10 the valve 48 is in its uppermost position it engages the valve seat 53 and closes the inlet end of the normal fuel system.

9 The valve 48 is provided with actuating mechanism by which it is controlled so as to close the 10 normal fuel system and open the starting fuel system for conditioning the carburetor for normal engine operation. This manipulation of the fuel valve may be accomplished by apparatus (not shown) which is adapted to be actuated by the 11 varying degrees of suction existing in the mixing chamber during cranking and during normal operation of the engine, respectively, or in any suitable manner, but in the forms illustrated, the fuel valve is operated in timed relation with 11 the choke valve 10 which, in practice, is closed to condition the carburetor for starting and opened to condition it for normal operation.

12 The valve actuating mechanism, illustrated in Fig. 5 includes a lever 57 which is pivotally mounted at 58 on a lug 59 extending outwardly from the side wall of the tubular structure 2. One end of the lever 57 has an aperture for receiving the valve stem 49 and the other end of the lever is located in registration with a cam 12 60 that is carried by the shaft 9 of the choke valve. Springs 61 and 62, mounted on the valve stem 49 bear between the respectively opposite sides of the apertured end portion of the lever 57 and spaced collars or nuts 63 and 64 on the 13 stem.

14 In operation, when the choke valve is rotated to its closed position shown in Fig. 5, the cam 60 turns the lever 57 in a counter-clockwise direction so as to hold the valve 48 off of the inner 13 extremity of the plug 35 and retain it in engagement with the valve seat 53. This action of the lever 57 opens the starting fuel system and closes the normal fuel system and places the spring 54 under compression. As the choke valve 10 is 14 rotated to its open position shown in Fig. 2, the cam 60 permits the lever 57 to be turned in a clockwise direction under the action of the spring 54 which urges the valve 48 downwardly, closing the starting fuel system and opening the normal fuel system. The characteristics of the springs 54, 61 and 62 may be suitably predetermined so as to permit a limited relative movement between the lever 57 and valve stem 49 during the initial opening of the choke valve. 15

In this way, the apparatus may be conditioned to maintain the normal fuel system inoperative and delay the closing of the starting fuel system during the initial opening of the choke valve to any desired degree.

With a carburetor of the above construction, the fuel ratios of the normal and starting fuel mixtures may be accurately predetermined independently by employing metering orifices of proper sizes. Since only one of the fuel systems are operable at a single time, with the exception of the period at which the change from one fuel system to the other is made, it is impossible for the fuel mixture produced by either fuel system 15 to be effected by the other.

The air bleed 46 which communicates directly with the starting fuel system and with the atmosphere assures a sufficient supply of air to properly atomize the fuel which is discharged 20 from the starting fuel system.

In carburetors for internal combustion engines of some types, it may be found unnecessary to shut off the starting fuel system during normal operation and in this event only a valve that is 25 adapted to render the normal fuel system inoperative during starting is required. Under such conditions, a carburetor of the form shown in Figs. 6 and 7 may be employed to advantage. This carburetor is mainly identical in its general 30 construction to the carburetor shown in Figs. 1 to 5 inclusive and it includes a central body portion 1' with which is integrally formed a tubular structure 2' having choke and throttle valves 10' and 20' at its respectively opposite ends. The 35 choke valve 10' has an auxiliary yieldable valve 16' which is operable by the suction in the mixing chamber 22'. This carburetor also includes a fuel reservoir 23' which is formed integrally with the central body portion 1' and which communicates with a well 24' in the lower end of the central body portion through a passage 25'. Formed in the central body portion 1' is a fuel 40 passage 26', joined at one end with the well 24' and communicating at its other end with the 45 mixing chamber. A Venturi throat 27' having an arm 28' that is provided with a passage 30' is located in the mixing chamber 22'. The passage 30' communicates with the fuel passage 26' at one end and with a fuel nozzle 29' at its other end. 50 The passages 26', 30' and the nozzle 29' form a normal fuel system for supplying fuel from the reservoir 23' to the mixing chamber of the carburetor during normal operation of the engine.

A vertically extending passage 65 having a 55 metering orifice 66 communicates at one end with the interior of the reservoir 23 and at its other end with a chamber 42' in the central body portion 1'. Extending through the chamber 42' and central body portion 1' is a tubular stem 43' which 60 has an enlarged threaded end 45' that is provided with an air bleed 46'. Formed in that portion of the stem 43' which is located in the chamber 42' are apertures 47' for admitting fuel from the passage 65 into the stem 43'. The stem 43' 65 and passage 65 form a starting fuel system which supplies fuel to the mixing chamber 22' independently of the normal fuel system.

The starting fuel system is at all times in communication with the source of fuel or reservoir 70 and even during normal operation of the carburetor, it may operate to supply a portion of the fuel required for such normal operation. If desired, the outlet of the starting fuel system may be placed sufficiently above the fuel level of the 75 reservoir to prevent the discharge of fuel during

normal engine operating. A valve 48' however, is provided in the well 24' to close the normal fuel system during starting so as to allow the starting fuel system to operate independently in producing a predetermined starting fuel mixture. 80 This valve is carried on a valve stem 49' which extends through a passage 50' in the central body portion by a spring 54' that bears at one end upon a collar 55' on the valve stem, and at the other end upon a threaded plug 56' located in the upper extremity of the passage 50'.

The fuel valve 48' is provided with actuating mechanism substantially identical to that shown in Fig. 5 which includes a pivotally mounted lever 57' having an aperture in one end through which the valve stem 49' extends. The respectively opposite sides of the lever 57' are engaged by springs 61' and 62' which bear at their outer ends upon collars or nuts 63' and 64', respectively. During closing of the choke valve 10', the lever 57' is rotated in a counter-clockwise direction by a cam (not shown) in Figs. 6 and 7, identical to the cam 60 shown in Fig. 5 so as to lift the valve 58' into engagement with the valve seat 53' at the upper end of the well 24'. This action 100 closes the normal fuel system as the carburetor is conditioned for starting by operation of the choke valve. The valve mechanism may also be manipulated by apparatus (not shown) which is operable by the changing degree of suction existing in the carburetor and fuel system of the engine. 105

With both forms of the invention, the outlet of the starting fuel may be extended from the carburetor and coupled into the manifold or connected in communication with any of the chambers of the engine which receive the fuel mixture.

The air entering the mixing chamber through the air bleed of the starting fuel system forms only a part of the quantity of air required to produce a suitable starting mixture and therefore provision is made to admit a controlled supply of air directly into the mixing chamber through the yieldable valve 16 in one form of the invention and 16' in the other form. This yieldable valve 115 120 is controlled by the suction in the mixing chamber and it may be calibrated, by predetermining the size of the opening and the tension of the spring 16, so as to accurately proportion the quantity of air drawn into the mixing chamber by the 125 suction created during cranking of the engine with respect to the fuel that is drawn into the mixing chamber by this suction from the calibrated fuel system.

Although but several specific embodiments of 130 this invention have herein been shown and described, it will be understood that various changes in the size, shape and arrangement of parts may be made without departing from the spirit of my invention and it is not my intention to limit its 135 scope other than by the terms of the appended claims.

What I claim is:

1. In an internal combustion engine having a 140 chamber for receiving a fuel mixture, a carburetor having a mixing chamber communicating with the fuel mixture receiving chamber of said engine, a choke valve in the air inlet of said mixing chamber for conditioning the air factor of said carburetor for starting, a normal fuel system including a 145 passage for supplying fuel to said mixing chamber, a starting fuel system having an independent outlet communicating with the fuel mixture receiving chamber of said engine, a fuel valve for positively closing said passage rendering said nor- 150

mal fuel system inoperative, means for operating said choke valve and said fuel valve in timed relation so as to open said fuel valve only when said choke valve is opened beyond a predetermined position, and yieldable means operable by the suction in said mixing chamber for controlling the direct supply of air thereto when said choke valve is closed.

2. In an internal combustion engine having a chamber for receiving a fuel mixture, a carburetor having a mixing chamber communicating with the fuel mixture receiving chamber of said engine, a choke valve in the air inlet of said mixing chamber for conditioning the air factor of said carburetor for starting, a normal fuel system for supplying fuel to said mixing chamber, a starting fuel system having an outlet communicating with the fuel mixture receiving chamber of said engine, a fuel valve for alternatively rendering said normal and starting fuel systems inoperative, means for operating said choke valve and fuel valve in timed relation so as to open the starting fuel system and close the normal fuel system when said choke is closed beyond a predetermined position, and to close the starting fuel system and open the normal fuel system when said choke valve is opened beyond a predetermined position, and yieldable means operable by the suction in said mixing chamber for controlling the direct supply of air thereto when said choke valve is closed.

3. In a carburetor including a body portion having a mixing chamber and having a pair of fuel passages therein, each connected with the other at one end and having an outlet end opening into said mixing chamber, a fuel reservoir in said body portion communicating with the connected ends of said fuel passages, a fuel nozzle in said mixing chamber communicating with the outlet end of one of said fuel passages, a fuel valve located at the connected ends of said passages and adapted to alternatively close said passages, a choke valve in the air inlet of said mixing chamber for conditioning the air factor of said carburetor for starting, and means for operating said fuel valve to close the fuel passage leading to said nozzle when said carburetor is conditioned for starting and to close the other fuel passage when said carburetor is conditioned for normal operation.

4. In a carburetor including a body portion

having a mixing chamber and having a pair of fuel passages therein, each connected with the other at one end and having an outlet end opening into said mixing chamber, a fuel reservoir in said body portion communicating with the connected ends of said fuel passages, a fuel nozzle in said mixing chamber communicating with the outlet end of one of said fuel passages, a fuel valve for closing the latter passage, the body portion of said carburetor having an air passage therein communicating with the other fuel passage for atomizing the starting fuel discharge, a choke valve in said mixing chamber for conditioning the air factor of said carburetor for starting, and means for operating said fuel valve to close the fuel passage leading to said nozzle when said carburetor is conditioned for starting.

5. A carburetor including a mixing chamber, a choke valve in the air inlet of said chamber having an auxiliary air inlet including a member movable to open position by suction when said choke valve is closed for controlling the main supply of air to said chamber during starting, a normal fuel system having a passage communicating with said mixing chamber, a starting fuel system having an outlet communicating with said mixing chamber and having an air bleed leading directly to said outlet, a fuel valve in said passage, and means for simultaneously closing said fuel and choke valves so as to condition said carburetor for starting.

6. In a carburetor, a fuel reservoir, a body portion having a mixing chamber and having a pair of fuel passages therein, each communicating with said fuel reservoir and having an outlet opening into said mixing chamber, a fuel nozzle in said mixing chamber communicating with the outlet end of one of said fuel passages, a fuel valve for closing the latter passage, a choke valve in the air inlet of said mixing chamber for conditioning the air factor of said carburetor for starting, means for operating said fuel valve to close the fuel passage leading to said nozzle when said carburetor is conditioned for starting, and yieldable means movable to open position when said choke valve is completely closed and operable by the suction in said mixing chamber for controlling the direct supply of air thereto when said choke valve is closed.
